UNITED STATES PATENT OFFICE.

IRA S. MOSHER, OF CHICAGO, ILLINOIS, ASSIGNOR TO MOSHER MANUFACTURING COMPANY, OF CHICAGO, ILLINOIS, A COPARTNERSHIP COMPOSED OF FREDERICK T. BARRETT AND IRA S. MOSHER.

JACK.

Application filed December 18, 1920. Serial No. 431,659.

To all whom it may concern:

Be it known that I, IRA S. MOSHER, a citizen of the United States, residing at Chicago, in the county of Cook and State of Illinois, have invented new and useful Improvements in Jacks, of which the following is a specification.

This invention relates to lifting jacks, and an object of the invention is to provide 10 a lifting jack of comparatively great lifting power which may be assembled in a compact form to permit it to be conveniently transported, and a jack which is particularly designed for use by motorists.

15 Another object of the invention is to provide, a jack structure embodying a supporting member which is movable independently of and relative to its raising means to permit quick adjustment of the supporting 20 means to engage the article to be raised, and also to provide means for holding the supporting means in adjusted position relative to its raising means, the latter means remaining in its lowermost normal position 25 during independent adjustment of the support.

A further object of the invention is to provide a lifting jack structure wherein interengaging ribs are provided on the supporting member and its raising means to prevent transmission of tilting strain to the raising means and consequently permitting of the free operation of the raising means.

30 Other objects of the invention will appear in the following detailed description and accompanying drawings wherein:

Fig. 1 is a side elevation of the improved lifting jack.

40 Fig. 2 is a side elevation of the lifting jack having parts broken away to illustrate the gearing for operating the lifting means.

Fig. 3 is a vertical section through the lifting jack.

45 Fig. 4 is a horizontal section through the lifting jack, taken on line 4—4 of Fig. 3.

Fig. 5 is an edged elevation of the lifting jack.

50 Fig. 6 is a side elevation of the raising member.

Fig. 7 is a detailed sectional view through the gear operating mechanism.

Fig. 8 is a side elevation of a handle used in the operating mechanism.

Fig. 9 is a cross section through the handle 55 taken on line 9—9 of Fig. 8.

Fig. 10 is a face view of the pawl employed for holding the supporting member in adjusted positions relative to its raising means.

60 Fig. 11 is a longitudinal section through the pawl taken on line 11—11 of Fig. 10.

Fig. 12 is a detailed edge elevation of the supporting member.

65 Fig. 13 is a fragmentary section through the supporting member illustrating the manner of nesting the operating handle therein and the means for holding the handle against accidental movement.

70 Fig. 14 is an edge elevation of the raising member.

Referring more particularly to the drawing, the improved lifting jack comprises a main supporting body 1 which is provided with a vertical longitudinal extending opening 2 that receives therein the raising sleeve 3. The raising sleeve 3 is substantially rectangular in shape in cross section and has its outer side split longitudinally, through 75 which the connecting portion 4 of the supporting member 5 extends. The connecting portion 4 has its inner edge connected to a substantially rectangular sleeve 6 which is slidably mounted within the sleeve 3 while its outer edge is connected to the extension 7 which provides the shelf 8 upon which the article to be raised rests. This connecting portion 4 is in the form of a web, and is shorter than the rectangular body 6. The extension 7 is provided with a transversely 80 extending opening 9 in which a pin 10 is mounted. The pin 10 rockably supports the pawl 11, the said pawl being relatively wide and provided with a cutout portion 12 to receive the extension 7 therein. The lower end 85 of the pawl 11 curves inwardly towards the axis of the sleeves 3 and 6 and has its inner lower edge rounded as shown at 13 for engagement in any aligning pair of notches 14 formed between the teeth 15 of the rack structures 16. The rack structures 16 are formed upon the raising sleeve 3 and are spaced, as clearly shown in Fig. 14 of the drawings, to permit the unimpeded passage 90 of the connecting portion 4 therebetween. The sleeve 6 and consequently the supporting member, of which this sleeve is a part, are slidably movable relative to the raising 95

100 structures 16. The sleeve 6 and consequently the supporting member, of which this sleeve is a part, are slidably movable relative to the raising 105

sleeve 3, so as to permit the supporting member to be raised or lowered independently of the operation of the raising sleeve 3 to permit proper engagement of the shelf 8 against the article to be raised, without necessitating operation of the raising sleeve 3. During the relative movement of the supporting member 5 of which the connecting portion 4 is a part, the pawl 11 is moved upon its pivot 10 out of the aligning pair of notches 14, and after the supporting member has been properly adjusted so that the shelf 8 will engage beneath the article to be raised the pawl 11 is swung inwardly so that it will 15 engage in the properly aligning notches 14 and the pawl 11 will connect the supporting member 5 and the raising sleeve 3 for synchronous movement.

The raising sleeve 3 is provided with a gear rack 17 extending longitudinally along the side opposite to the racks 16 as clearly shown in Fig. 6 of the drawings. The teeth 18 of the rack 17 mesh with the peripheral teeth 19 of the gear 20. The gear 20 has a trunnion 21 formed integrally therewith which rotatably engages in a suitable bearing 22 formed in the housing 1 of the jack structure, as clearly shown in Fig. 4 of the drawing. The gear 20 has a bearing sleeve 23 formed integrally therewith which is slightly larger in diameter than the gear 20 and which snugly fits within the bearing 24 formed in the housing 1. The worm gear 25, of greater diameter than the gear 20, is formed integrally upon the outer end of the sleeve 23. A worm 26 is mounted upon the shaft 27 carried by the casing 1 and meshes with the worm gear 25. Roller bearings 28 are carried by the worm 26 to absorb under thrust of the worm 26 and consequently relieve the friction which might be occasioned during the rotation of the worm. The worm gear 25 and worm 26 are enclosed in a suitable casing 29 formed upon the body 1 and removable casing section 30, by means of which access to the gears is obtained when necessary.

The shaft 27 has a ratchet 31 keyed thereon about which a housing 32 is mounted, the latter housing being rotatable upon the shaft 27 and provided with a pair of rotating arms 33, one positioned above and one below the axis of the shaft 27. Pawls 34 are pivotally carried by the arms 33 and one of these pawls is adapted to engage the ratchet teeth, of the ratchet 31 at a time to rotate the ratchet and consequently the shaft 27 by movement of the housing 32 upon the shaft 27. The housing 32 has a socket 35 formed thereon which is adapted to receive one end of the handle 36. This handle 36 may be constructed in any approved manner, preferably of hollow tubing as shown in Figs. 8 and 9 of the drawings and it has a knob 37 on one end to act as a hand grip. By pivotal

movement of the handle 36, which forms a lever when inserted in the socket 35, the shaft 27 may be rotated, which in turn rotates the gear 20 through the worm 26 and worm gear 25 and moves the raising or lowering supporting member 5 when the pawl 11 is engaged in one of the notches 14. Suitable fastening means, such as the set screw 40 and spring 41, may be provided, the set screw being carried by the connecting portion 4 and having one end of the spring connected thereto while the other end of the spring is connected to the pawl 11, for maintaining the pawl 11 in one of the notches 14, against accidental movement.

The sleeve 6 is provided with longitudinally extending axial recess 44 which provides a pocket for receiving the handle 36, when the latter member is not in use, to provide a compact structure for the jack which may be stored in a relatively small space. A set screw 45 is carried by the sleeve 6 and is adapted for biting engagement with the handle 36 to hold it against accidental movement relative to the sleeve 6 when the handle is nested in the pocket 44.

The body 1 is provided with vertical ribs 46 which engage in recesses 47, which are formed in the raising sleeve 3. The recesses 47 form ribs 48 which interengage with the ribs 46 to prevent the transmission of tilting movement or strain to the gear rack 17 and consequently to the gear 20 which would increase the work and decrease ease of operation of the jack structure.

If it is so desired, a hand crank 50 may be mounted upon the shaft 27 to permit manual rotation of this shaft and operation of the raising sleeve 3. This hand crank 50 is particularly adapted for use when only light weights are to be lifted and it will also serve admirably in lowering the sleeve 3 into its normal position.

From the foregoing description taken in connection with the accompanying drawings it will be apparent that the supporting member 5 may be raised or lowered relative to the raising sleeve 3 to permit the shelf 8 to properly engage the article to be raised and also that the raising sleeve 3 will remain in its lowermost position during such adjustment, thus permitting effective working use of the entire lifting or raising of the raising sleeve 3 and eliminating the tedious operation of raising the support through operation of the gear 20, to cause it to properly engage the article to be raised.

The forming of the gear 20, trunnion 21, bearing sleeve 24 and worm gear 25 integral, provides a relatively strong structure having a minimum bearing surface which will materially increase the durability and strength of the jack structure.

It is, of course, to be understood that the invention may be constructed in various

other manners and the parts associated in different relations and, therefore, I do not desire to be limited in any manner except as set forth in the claims hereunto appended.

5 Having thus described my invention what I claim is:

1. A jack comprising a body provided with a vertical opening, a sleeve slidably mounted in the opening and having a tongue 10 and groove connection with the body, a second sleeve slidably mounted within the first sleeve, a shelf extending from the second sleeve, and adjustable connection between said shelf and the first sleeve, and means 15 for raising the first sleeve.

2. A jack comprising a body provided with a vertical opening, a sleeve slidable in said opening, a second sleeve slidably

mounted within said first named sleeve, a transverse shelf on said second sleeve, an 20 adjustable connection between said shelf and said first named sleeve, and means for raising said first named sleeve.

3. A jack comprising a body provided with a vertical opening, a sleeve slidable in 25 said opening, a second sleeve slidably mounted within said first named sleeve, a transverse shelf on said second sleeve, said first named sleeve provided with a series of notches at one side thereof, a pawl pivoted 30 to said shelf and engageable in said notches to adjustably support said shelf relative to the first named sleeve, and means for raising the first named sleeve.

In testimony whereof I affix my signature.
IRA S. MOSHER.
